CLAIM

We claim the ornamental design for erogenous stimulator, as shown and described.

DESCRIPTION

FIG. 1 is a left side view of the erogenous stimulator.

FIG. 2 is a front view of the erogenous stimulator shown in FIG. 1.

FIG. 3 is a right side perspective view of the erogenous stimulator shown in FIG. 1.

FIG. 4 is a right side view of the erogenous stimulator shown in FIG. 1.

FIG. 5 is top view of the erogenous stimulator shown in FIG. 1.

FIG. 6 is a bottom view of the erogenous stimulator shown in FIG. 1; and,

FIG. 7 is a rear view of the erogenous stimulator shown in FIG. 1.
